UNITED STATES PATENT OFFICE

2,253,494

REVERSIBLE SLIDER FOR SLIDE FASTENERS

Alfred E. Carlile, Meadville, Pa., assignor to Talon, Inc., a corporation of Pennsylvania

Application March 25, 1940, Serial No. 325,763

6 Claims. (Cl. 24—205.5)

This invention relates to slide fasteners and, in particular, to the provision of new and improved sliders for use therein.

It is an object of this invention to provide an improved slider for slide fasteners which may be readily and conveniently operated from either side.

It is a further object of this invention to provide such a slider wherein manually engageable pull means of cord-like form is movably secured to the slider in such manner that it may be readily engaged from either side of the slider, extended on that side, and readily manually engaged at a great number of angles and positions for opening and closing a slide fastener by longitudinal movement of the slider with respect to the fastener.

It is a further object of this invention to provide a slider construction which is reversible, which is of simple and cheap construction, which is extremely durable, and which is of pleasing appearance.

These and other objects and advantages of the invention will appear from the following description taken in conjunction with the accompanying drawing, which forms a part thereof, and will be pointed out in the appended claims.

In the drawing:

Fig. 1 is a view, in perspective, of a slide fastener slider according to this invention, as applied to one conventional form of slide fastener; applied to one conventional form of slide fastener;

Fig. 2 is a longitudinal central section of the slider of Fig. 1, with the pull member in elevation;

Fig. 3 is a view similar to Fig. 2, but showing the pull member in reversed position; and

Fig. 4 is a transverse section taken substantially on the line 4—4 of Fig. 2.

In various applications of the slide fastener, and, in particular, in their application to reversible garments such as coats or jackets, it is found desirable to have the slider operated from either side of the fastener, and of the reversible garment.

Formerly, use has been made in such applications of sliders having lugs of different type at opposite sides thereof, each of which lugs is provided with pull tabs.

In other constructions, the slider was provided with a track or retaining slide extending over one wing or side of the slider, over the neck of the slider and over the other wing or side of the slider. A plate-like pull tab was slidably supported on this track or retaining slide for movement from one side to the other side of the slider,

whereby the slider might be operated by the same pull tab from either side of the slider, and of the fastener.

Both of these constructions proved extremely inconvenient and uncomfortable in use because of the projection formed on the underside of the slider, by the second pull tab in the first case, and by the track or retaining slide in the second case.

Because of the necessity for the second pull tab in the first case, and the necessity for an extremely intricate and costly design of the retaining slide in the second case, the cost of these slider constructions was substantially increased over conventional sliders operable from one side only.

In addition to the above disadvantages, the projection formed by the second pull tab in the first case, and by the track or retaining slide in the second case, proved a great disadvantage or inconvenience due to its catching in clothing and in the skin of wearers of a garment provided with slide fasteners having such sliders.

All of the above disadvantages of these prior art constructions are totally obviated, according to this invention, by the provision of a single flexible pull member which is slidable endwise through an aperture or bore provided in the slider body, which pull member is provided at each end with a stop member for retaining it in the bore or aperture, and for limiting its endwise movement in both directions.

Referring to the drawing, wherein I have illustrated one application of the principles of this invention, a slider, generally designated 10, is shown in its operative relation in a conventional slide fastener. The slide fastener includes a pair of stringers 5, each comprising a tape 6 having a reinforced edge 7 upon which is secured a row of interlocking fastener members 8. The interlocking fastener members 8 of the stringers 5 are progressively engaged and disengaged in known manner by sliding movement of the slider 10 longitudinally of the fastener 45 stringers 5. Conventional means such as the bottom stop 9 is provided for securing the ends of the stringers 5 together, below and adjacent the rows of interlocking fastener members 8.

The body of the slider 10 comprises a pair of similar sides or wings 11 secured together at their upper ends by a neck or wedge member 12 and having marginal side flanges 14 which cooperate with the lateral surfaces of the wedge member 12 to form an upwardly diverging substantially Y-shaped fastener member receiving

channel for slidably supporting interlocking fastener members 8 in known manner. If desired, suitable automatic locking means of the "wing" lock" type may be provided by the formation of locking projections or edges on the flanges 14 or by shaping these flanges, for instance, in the manner described in my copending application Serial No. 285,375, filed July 19, 1939, which matured into Patent No. 2,214,705, granted September 10, 1940. Extending from side to side through the body of the slider 10 at its upper end is a pull member receiving bore or aperture 15 which is preferably disposed centrally of the width of the slider 10. Extending through this bore or aperture 15 is a cord-like flexible pull member 16 having similar stop members 17 and 18 secured to its opposite ends.

In order partially to recess the cord-like or cable-like flexible pull member 16 in the exterior wing 11 of the slider in its inoperative position (shown in dash lines in Fig. 2), each wing 11 of the slider is provided with a longitudinal recess or channel 19 extending from the end of the bore 15 to the lower edge of each wing 11. As shown in Figs. 2 and 3, the end edges of the bore or aperture 15 are bevelled at 20 in order to enhance the flexibility of the pull member 16.

The flexible pull member 16 may be formed of any suitable textile or other material and may fit snugly in the receiving bore or aperture 15, though readily manually movable endwise therethrough between the extreme positions shown in Figs. 2 and 3, respectively. When the fastener is to be operated from one side, the pull member will take one of the extreme positions of adjustment, with respect to the slider, as shown in Figs. 2 or 3.

If it is desired, after operating the slider from one side of the fastener (as shown, for instance, in Fig. 2) to operate the slider from the opposite side of the fastener (as shown, for instance, in Fig. 2), the appropriate end stop member, such as 18 in Fig. 2, is manually pulled outwardly of the slider to bring the flexible pull member 16 to its extreme reverse position (as shown in Fig. 3, for instance).

While a regular or non-separating bottom stop is shown in Fig. 1, for convenience of illustration, it is, of course, to be understood that other known forms of stringer end attaching means, such as separable bottom end fittings may be used. Separating bottom end fittings will, in fact, most probably be used in such relationships as in reversible garments where the use of such a slider, as is described above, and illustrated in Figs. 1 to 4, is most desirable.

It is, of course, to be understood that the above description is merely illustrative of the principles of this invention and in nowise limiting and that I desire to comprehend within this invention all modifications included within the scope of the appended claims.

Having thus fully described my invention, what I claim as new and desire to secure by Letters Patent is:

1. In a reversible slider for slide fasteners, a

slider body having an interlocking fastener member receiving channel therein, and a flexible pull member extending through said slider body from front to back and movable endwise therethrough.

5 2. In a reversible slider for slide fasteners, a slider body having an interlocking fastener member receiving channel therein, a flexible pull member extending through said slider body from front to back and movable endwise therethrough, and stop means on said pull member for limiting endwise movement of said pull member with respect to said slider body.

15 3. In a reversible slider for slide fasteners, a slider body comprising a pair of similar wing members secured together at their upper ends by an intermediate wedge member, a bore extending through said wedge member and said wings from front to back of said slider, and a flexible cord-like pull member extending through

20 said bore from side to side of said slider body and slidably endwise in said bore from front to back of said slider.

25 4. In a reversible slider for slide fasteners, a slider body comprising a pair of similar wing members secured together at their upper ends by an intermediate wedge member, a bore extending through said wedge member and said wings from side to side of said slider, a flexible cord-like pull member slidably endwise in said bore from side to side of said slider, and stop means at each end of said pull member abuttingly engaging opposite ends of said bore for limiting endwise sliding movement of said flexible pull member and retaining said flexible pull member in said bore.

30 5. In a reversible slider for slide fasteners, a slider body comprising a pair of similar wing members secured together at their upper ends by an intermediate wedge member, a bore extending through said wedge member and said wings from front to back of said slider, and a flexible cord-like pull member secured in said bore for endwise sliding movement from front to back of said slider.

35 6. In a reversible slider for slide fasteners, a slider body comprising a pair of similar marginally flanged wing members secured together at their upper ends by an intermediate wedge member forming with the flanges of said wing members an upwardly diverging interlocking fastener member receiving channel, a bore extending through said wedge member and said wings from side to side of said slider, a flexible cord-like pull member slidably endwise in said bore from side to side of said slider, stop means at each end of said pull member abuttingly engageable with opposite ends of said bore for limiting endwise sliding movement of said flexible pull member and retaining said flexible pull member in said bore, and a pull member receiving channel in each wing, extending from the end of said bore, for partially recessing said flexible pull member in said slider wing when extended at that side of the slider.
